ROY J. WENSLEY, OF EDGEWOOD, THOMAS U. WHITE, OF PITTSBURGH, AND JOHN E. GARDNER, OF WILKINSBURG, PENNSYLVANIA, ASSIGNORS TO WESTINGHOUSE ELECTRIC & MANUFACTURING COMPANY, A CORPORATION OF PENNSYLVANIA.

SUPERVISORY CONTROL SYSTEM.

Application filed February 1, 1924. Serial No. 689,975.

Our invention relates to supervisory control systems and particularly to systems for supervising and controlling electrical equipment remotely disposed with respect to the 5 control station.

One of the objects of our invention is to provide an improved relay selecting means for selecting the apparatus units and supervisory signalling devices at the remote point 10 and central station, respectively.

Another object of our invention is to provide a high-speed system for controlling remotely-disposed apparatus from a central point.

15 Another object of our invention is to provide controlling means for synchronizing the operation of a selecting chain of relays at both the dispatcher's office and the substation.

Another object of our invention is to so 20 arrange a controlling circuit that it is impossible to cause false operation either of the apparatus unit or of the supervisory signalling device.

Another object of our invention is to provide 25 signalling circuits operating in conjunction with the synchronized relay chain for operating the apparatus units and supervisory signals by means of alternating current.

Another object of our invention is to provide 30 means for simultaneously operating an apparatus unit at the substation and receiving an answer-back signal over a single signalling circuit.

Another object of our invention is to provide 35 means for stopping the operation of the relay chains and for restarting their operation in the event that the relays of the chain do not operate synchronously.

A further object of our invention is to provide 40 means for simultaneously operating a plurality of circuit breakers and supervisory signals without interference between the operations.

There are other objects of the invention 45 which, together with the foregoing, will be described in the detailed specification which is to follow.

Referring now to the drawings, comprising 50 Figures 1 to 4, inclusive, the invention is shown applied to a system for supervising an automatic substation from a central control or dispatcher's office.

The apparatus shown in Figs. 1 and 2 is

that located at the dispatcher's office, while the apparatus shown in Figs. 3 and 4 is that 55 located at the substation.

While the invention has been shown applied to the supervision and control of only one substation, it will be obvious from its description how a large number of such sub- 60 stations may be controlled and supervised from a dispatcher's office.

In order to facilitate an understanding of the invention, the apparatus and operation will first be described generally. A chain 65 of counting relays is provided at the dispatcher's office. In this instance, there are fifty counting relays in the chain. A corresponding chain of counting relays is located at the substation. Only a portion of the 70 fifty counting relays in the chain has been shown. However, from the circuits drawn, it will be evident that a larger number are connected. It is, of course, obvious that this counting relay chain may comprise any number 75 of relays, the number 50 being chosen merely for convenience.

A trunk line extends from the dispatcher's office to the substation. Controlling relays and circuits are associated with this trunk 80 line for controlling the operation of the chain relays at both the dispatcher's office and the substation. Two wires are necessary in the trunk line for operating the controlling circuit. An extra signalling conductor is pro- 85 vided in the trunk line for each fifty circuit breakers at the substation that are to be controlled and supervised.

When a circuit breaker in the substation 90 operates under automatic control, the controlling circuits function at both the substation and the dispatcher's office and the first relay of the chain at both the dispatcher's office and the substation are operated, then the second relay of the chain, and then the 95 third relay of the chain, and so on.

When the predetermined relay in the chain at the substation, that is associated with the apparatus unit or circuit breaker that is operated, is energized, an alternating current 100 is sent over a predetermined signalling conductor and through a circuit resonant to the frequency of the alternating current applied, a relay is operated which, in view of the fact that the corresponding relay in the chain at 105 the dispatcher's office is operated, causes the

supervisory signalling device to be changed to indicate the operation of the apparatus unit.

In the meantime, at the substation, the application of the signalling current to the signalling conductor causes the controlling circuit to be interrupted until the particular supervisory signalling device at the dispatcher's office has been operated, whereupon the controlling circuit is permitted to function to energize the next relay in the chain. In the event that the circuit breaker at the substation is operated to a position opposite from that assumed, a different frequency of alternating current is applied to the signalling conductor to operate a different relay through a circuit which is resonant to that particular frequency, and a different signalling device is operated in accordance therewith.

In order to enable the dispatcher to operate an apparatus unit at the substation, he is provided with a number of keys, one for each apparatus unit. These keys may be operated in two directions, depending upon the operation that it is desired to have the unit perform. When the dispatcher desires to control an apparatus unit, he throws the key corresponding to that unit in the proper direction and, by this means, the controlling circuit begins to function to cause the successive energization of the relays in the relay chain at the dispatcher's office and the substation. When the chain relay that is associated with the operated key is energized, alternating current of a definite frequency is applied to the same signalling conductor, as before mentioned, to operate through a circuit resonant to that frequency another relay at the substation that is associated with the apparatus unit which it is desired to operate. This is caused by reason of the fact that the corresponding relay in the relay chain at the substation is now energized. The operation of the controlling circuit is interrupted until the selected relay is energized, whereupon the control circuit functions as before.

The foregoing is the operation when it is desired to control a maximum of fifty circuit breakers, or other apparatus units. In the event that it is desired to control a larger number, a separate signalling conductor for each fifty and separate contacts on each of the relays of the relay chain are provided.

Referring now more particularly to Fig. 1, a key K is of the ordinary double-throw type. Generators G and G' are indicated diagrammatically and are provided for the purpose of generating alternating currents having frequencies of substantially 500 cycles and 700 cycles, respectively. A key K-1 is of the ordinary release type and may be operated in but one direction.

A relay group RG comprising relays 15 to 24, inclusive, is a chain of counting relays corresponding to those previously mentioned.

These relays are of somewhat special construction, being provided with two windings, the lower winding of which is of high resistance and of relatively few ampere turns and is adapted, when energized, to attract only certain of the armatures of the relay. When the upper winding of the relays is energized, the remaining armatures are operated. The armatures that are operated by the lower winding are shown as a rectangle, while the armatures operated by the upper and lower windings in series are shown in the usual manner.

A relay 26 is a polarized relay of the ordinary type and controls supervisory control relays 27 and 28. The relays 27 and 28 control supervisory signalling devices 129 and 130. The relays 30 to 34, inclusive, are associated with the signalling circuit, while relay 29 is a relay for controlling the circuits of the counting relay chain in a manner which will appear later. F-6, F-7, F-8, F, F-1 and F-2 are wave filters which pass only alternating currents of predetermined frequencies, as will appear. Relays 150 to 153, inclusive, inform the dispatcher when the signalling circuit does not function.

Relays 200 to 220, inclusive, comprise a controlling circuit for controlling the operation and functioning of the counting relay chain.

In Fig. 3 is shown a counting relay group comprising a chain of counting relays 300 to 309, inclusive, which are constructed similarly to the counting relays previously mentioned. Generators G-2 and G-3 are provided for supplying alternating currents the frequency of which is 900 cycles and 1100 cycles, respectively.

F-4, F-5, F-3, F-9, F-10 and F-11 are wave filters that are associated with the signalling conductors and are resonant to predetermined frequencies, as will appear.

Relays 314 to 318, inclusive, are associated with the signalling conductor 160. Relays 319, 311, 312 and 313 are associated with a circuit breaker C and are provided for the purpose of controlling the operation of this breaker. Relays 440 to 443, inclusive, function when the signalling circuit is out of order. A relay 321 is a common relay in series with the battery supply lead to all of the circuit breakers to be controlled. The circuit breaker C is of an ordinary type provided for the purpose of tieing feeder circuits together, or starting a rotary converter, or other translating device.

Relays 500 to 517, inclusive, comprise the controlling circuit at the substation. In the present instance, the dispatcher's office is connected to the substation by means of the trunk line comprising four conductors 159, 160, 280 and 281.

In the drawings, a grounded battery has been shown. However, it is quite obvious that a metallic conductor may be used for

this common ground, and, in this instance, there would be a five-conductor trunk line between the substation and dispatcher's office.

The apparatus shown in the drawings having been described in general, its detailed operation will now be explained. For this purpose, it will be assumed that the circuit breaker C is closed. This may be caused by the operation of the relay 322 under the control of automatic devices (not shown) that are responsive to circuit conditions in any well known manner. When the circuit of the closing coil 323 of the circuit breaker C is completed, a circuit is also completed for the relay 321 over a path extending from ground by way of the armature 420 and its front contact, through the closing coil 323, through the winding of the low-resistance common relay 321, to battery. The relay 321, upon being energized, completes a circuit extending from ground by way of armature 419 and its front contact, conductor 430, armature 529 and its back contact, and through the upper winding of the relay 504 to battery. The relay 504 is of the same construction as the counting relays previously mentioned and, with its upper winding energized, causes the armature 530 to engage its front contact, whereby a circuit is prepared for its lower winding.

When the circuit breaker C closes, the operating circuit of the closing coil 323 is opened and the short-circuit is removed from the lower winding of the relay 504. The relay 504 is now completely energized and, upon operating, causes a circuit to be prepared at armature 529 for the relay 505, causes the circuit of the relay 503 to be opened at armature 567, and causes one point in the circuit of the relay 506 to be opened at armature 531.

The relay 503 is normally energized over a path including the trunk conductors 280 and 281. The circuit of this relay may be traced from ground at the battery B-4 (Fig. 2) by way of armature 238 and its back contact, through the lower winding of the relay 206, the back contact and armature 246, armature 271 and its back contact, armature 273 and its back contact, armature 275 and its back contact, conductor 280, back contact and armature 541, back contact and armature 542, back contact and armature 545, armature 526 and its back contact, lower winding of relay 503, armature 567 and its back contact, upper winding of relay 503, back contact and armature 525, winding of the polarized line relay 511, conductor 281, the winding of polarized line relay 217, armature 245 and its back contact, upper winding of relay 206, and thence by way of back contact and armature 237 to battery.

It will be noted that, inasmuch as the relays 206 and 503 at the dispatcher's office and substation, respectively, are energized over

the above circuit, the windings of the polarized line relays 217 and 511 are short-circuited and, therefore, they do not appear in the above circuit. Inasmuch as the circuit of the relay 503 is opened by the energization of the relay 504, this relay is deenergized and a circuit is closed, at armature 527 and its back contact, for the relay 502. Also, the short-circuit is removed from the polarized line relay 511 by the retraction of the armature 528. The deenergization of the relay 503 also removes ground at armature 527 from the conductor 431, whereby the relay 320 is deenergized and battery is supplied, through the armatures 417 and 418, to the various relays at the counting chain and to the battery conductor 432.

The relay 502, upon being energized, at armature 524, establishes a locking circuit for itself, at armature 525, opens another point in the circuit of the relay 503 and, at the front contact of this armature and the front contact of the armature 526, connects the relay 500 across the trunk conductors 280 and 281 in series with the polarized line relay 511.

At the dispatcher's office, inasmuch as the circuit of the relay 206 is also opened by the operation of the relay 504 at the substation, this relay is deenergized and a circuit is closed, at armature 293 and its back contact, for the relay 207, while, at armature 243, a short-circuit is removed from the polarized line relay 217 and, at armature 293, opens the circuit of the relay 29 and this relay is permitted to deenergize to apply potential through the armatures 122 and 123 to all the relays of the counting chain at the dispatcher's office and also to the battery supply conductor 142.

The relay 207, upon being energized, establishes a locking circuit for itself at armature 244, at armatures 245 and 246, opens another point in the circuit of the relay 206 and, at the front contacts of these armatures, completes a circuit for the polarized line relays 217 and 511 in series with the relays 209 and 500. This circuit may be traced from ground through the lower winding of relay 209, back contact and armature 248, front contact and armature 246, armature 271 and its back contact, armature 273 and its back contact, armature 275 and its back contact, conductor 280, back contact and armature 541, back contact and armature 542, back contact and armature 545, armature 526 and its front contact, armature 522 and its back contact, winding of relay 500, back contact and armature 521, front contact and armature 525, winding of polarized line relay 511, conductor 281, winding of the polarized line relay 217, armature 245 and its front contact, armature 247 and its back contact, and upper winding of relay 209 to battery. The relays 209, 217, 511 and 500 are operated over the above circuit.

Another result of the operation of the re-

lay 207 is that, at armature 287, a circuit is completed for the relay 201 which, upon operating, establishes a locking circuit for itself at armature 226, and at armature 227 completes a circuit for the buzzer alarm signal 200. By the operation of this buzzer, the attention of the dispatcher is drawn to the fact that the apparatus is about to function.

It will be assumed that the relays 217 and 511 are operated in such direction as to cause the armature 270 to engage the contact 276 and to cause the armature 546 to engage the contact 548. A circuit is completed by the operation of the armature 270 that extends 15 from ground by way of said armature, contact 276, winding of the relay 216, conductor 142, and armature 123 and its back contact to battery.

The relay 216 is energized over the above 20 circuit and operates, at armature 267, to open one point in the locking circuit of the relay 215, to establish a locking circuit for itself at armature 268, to complete a circuit at armature 266 for the timing relay 213 and to prepare a circuit at armature 269 for the lower winding of the relay 15. The operation 25 of the armature 546 into engagement with the contact 548 completes a circuit extending from ground by way of said armature and contact, winding of relay 512, conductor 432, and back contact and armature 418 to battery. The relay 512 is energized over the above circuit and, upon operating, at armature 568 establishes a locking circuit for 30 itself, at armature 550 opens one point in the locking circuit of the relay 513, completes a circuit at armature 549 for the timing relay 515, and prepares a circuit at armature 551 for the lower winding of the relay 300.

At the dispatcher's office, the relay 209, upon energizing, at armature 250 completes a circuit extending from ground by way of the front contact and said armature, front contact and armature 269, conductor 147, back contact and armature 43, lower winding of the first counting relay 15, back contact and armature 51, back contact and armature 57, back contact and armature 64, back contact and armature 71, back contact and armature 78, back contact and armature 85, back contact and armature 92, back contact and armature 99, back contact and armature 106, back contact and armature 109, and armature 122 and its back contact to battery. When the lower winding of the relay 15 is energized, this relay operates to attract the armatures 41 and 42.

At the substation, the relay 500, upon being energized, completes a circuit, at armature 520, extending over a path from ground by way of front contact and said armature, front contact and armature 551, conductor 425, back contact and armature 329, lower winding of the first counting relay 300, back contact and armature 337, back contact and arm-

ature 344, back contact and armature 351, back contact and armature 358, back contact and armature 365, back contact and armature 372, back contact and armature 379, back contact and armature 386, back contact and armature 393, back contact and armature 396, and back contact and armature 417 to battery. With its lower winding energized, the first counting relay 300 is adapted to attract the armatures 327 and 328.

Returning now to the operation of the relay 15, the engagement of the armature 41 with its front contact completes a circuit extending from ground by way of front contact and said armature, armature 40 and its back contact, conductor 146, and winding of relay 218 to battery. The relay 218 is energized over the above circuit and operates, at armature 271, to open one point in the circuit of the relays 209, 217, 511 and 500 and, at armature 272, operates to complete a circuit for the relay 208.

The relay 209, upon deenergizing, at armature 250, opens the short-circuit around the upper winding of the relay 15, whereby this winding is permitted to function and the armatures 40, 43, 44, 45 and 171 on the said relay are completely operated. The relay 208, upon being energized, at armature 249, establishes a locking circuit for itself and, at armatures 247 and 248, reverses the connections of the windings of the relay 209 with respect to the trunk conductors 280 and 281.

The operation of the relay 15 prepares at armature 45 a signalling circuit that includes the polarized relay 26, at armature 44 prepares a circuit for the lower winding of the relay 16, at armature 43, opens the energizing circuit of the lower winding of the relay 15, and at armature 40 opens the previously traced circuit for the relay 218. This relay is deenergized to open at armature 272 the original operating circuit of the relay 208 and to restore at armature 271 one point in the line circuit. The relay 208 does not deenergize at this time, for the reason that its locking circuit is maintained at armature 274 of the relay 219.

At the substation, the operation of the armature 327 of the relay 300 completes a circuit extending from ground by way of front contact and said armature, armature 326 and its back contact, conductor 427, and the winding of relay 580 to battery. The relay 580 is energized over the above circuit and operates at armature 584 to establish a locking circuit for itself, and at armature 583 completes a circuit for the relay 510. The relay 510 is energized and operates, at armature 545, to open one point in the circuits of the relays 209, 217, 511 and 500, and at armature 544 completes a circuit for the relay 501. The relay 501, upon being operated, at armature 523 establishes a locking circuit for itself, 130

and at armatures 521 and 522 reverses the connections of the winding of the relay 500 with respect to the trunk conductors 280 and 281. By the opening of the line circuit by reason 5 of the operation of the relay 218 and the relay 510, the relay 500 is deenergized and the short-circuit is removed from the upper winding of the relay 300, which is permitted to completely attract the armatures 326, 329, 10 330, 331 and 480.

By the operation of the armature 331, as the circuit breaker C is in a closed position and the relay 313 is energized, a circuit is completed extending from the grounded pole 15 of the 1100 cycle alternating-current generator G-3, front contact and armature 402, armature 331 and its front contact, winding of the alternating-current relay 314, wave filter F-4, signalling conductor 160, wave filter F-1, winding of the alternating-current relay 33, armature 125 and its back contact, armature 124 and its back contact and thence to ground. The alternating-current relays 314 and 33 are energized over the above circuit. 25

It will be noted that the wave filters F, F-2, F-3 and F-5 are also included in the above circuit. However, as the wave filter F permits current of 900 cycle frequency 30 only to pass, the wave filter F-2 permits current of 500 and 700 cycle frequency only to pass, and the wave filters F-5 and F-3 permit current of 500 and 700 cycles only to pass, respectively, these other paths can be 35 neglected when a current of a frequency of 1100 cycles is traversing the signalling circuit.

The relay 314, upon being energized, at armature 408 completes a circuit extending from ground by way of the front contact and 40 said armature, conductor 429, through the winding of the relay 508, and thence to battery. The energization of this relay opens one point in the line circuit, that includes the relays 209, 217, 511 and 500, to prevent operation 45 of the same at this time. Another circuit is completed in multiple with the circuit of the relay 314 which extends through the winding of the alternating-current relay 440, and thence through an artificial line L to ground. The relay 440 is energized over the 50 above circuit and operates, at armature 444, to complete a circuit for the upper winding of the slow-to-operate relay 441 in the event that the relay 314 is not energized. The reason 55 for this will be explained subsequently.

The energization of the alternating-current relay 33, at the dispatcher's office, completes a circuit extending from the positive pole of the battery B through the winding of the 60 low resistance relay 30, armature 127 and its front contact, front contact and armature 45, and winding of polarized relay 26 to the midpoint of the battery B. The polarized relay 26 operates its armature 110 in such direction as to connect the contacts 111 and 112. 65

As a result of this connection, the relay 27 is energized over a circuit from the negative side of battery B, through the winding of relay 27, the front contacts and armature 111 and 112, armature 45 and its front contact, the front contact and armature 127 to the winding of relay 30 to the positive side of battery B. Upon operating, the relay 27, at armature 117, establishes a locking circuit for itself, at armature 118 completes a circuit 70 for the supervisory lamp 129, and at armature 116 opens the locking circuit of the relay 28. The operation of the supervisory lamp 129 apprises the dispatcher of the operation of circuit breaker C at the substation. Another result of the operation of the relay 27 is that a circuit is completed extending from the midpoint of the battery B, through back contact and armature 119, armature 117 and its front contact, contacts 111 and 112 on 75 the polarized relay 26, armature 45 and its front contact, front contact and armature 127, and winding of relay 30 to the positive pole of the battery B. 80

The relay 30 is energized over the above 90 circuit, on account of the relay 26 no longer being in its circuit, and operates, at armature 124, to open the circuits of the wave filters F-1 and F-4 whereby the circuit of the relay 314 at the substation is opened, as is the 95 circuit of the relay 33. The deenergization of the relay 33 is followed by the deenergization of the relay 30.

The relay 314, upon being deenergized, opens the circuit of the relay 508, and this 100 relay retracts its armatures to restore the line to normal condition, whereby the relays in the line circuit are energized over a path which will be described subsequently.

When the relay 508 is first energized, the 105 locking circuit of the relay 580 is opened and this relay retracts its armatures, thereby causing the restoration of the relay 510. The latter relay retracts its armatures to restore one point in the line circuit and to open the 110 original energizing circuit of the relay 501.

When the relay 508 is deenergized, as previously mentioned, a circuit is completed for the relays in the line circuit over the following path: from ground through the lower 115 winding of relay 209, front contact and armature 247, front contact and armature 245, winding of the polarized line relay 217, conductor 281, winding of polarized line relay 511, armature 525 and its front contact, armature 521 and its front contact, winding of relay 500, front contact and armature 522, front contact and armature 526, armature 545 and its back contact, armature 542 and its back contact, armature 541 and its back contact, 120 trunk conductor 280, back contact and armature 275, back contact and armature 273, back contact and armature 271, armature 246 and its front contact, armature 248 and its front contact, and upper winding of relay 209 to 130

battery. The relays 209, 217, 511 and 500 are energized over the above-traced circuit.

By the operation of the relay 217, the armature 270 is forced into engagement with its contact 277, while, by the operation of the relay 511, the armature 546 is forced into engagement with the contact 547. By the operation of the armature 270, a circuit is completed for the relay 215. This relay, 10 upon being energized, at armature 264, operates to open the locking circuit of the relay 216, which is deenergized, to establish a locking circuit for itself at armature 278, to complete a circuit for the timing relay 214 15 at armature 263, and to prepare a circuit for the lower winding 16 of the relay chain at armature 265. The relay 216, upon retracting its armatures, establishes the previously mentioned locking circuit for the relay 215 20 at the armature 267.

There is a possibility that the control circuit at both the dispatcher's office and station will not cause proper functioning of the apparatus. This may occur for any one of a 25 number of reasons. That is, the proper counting relays at the dispatcher's office or station may not operate, or the signal may not be received from the station designating the condition of the particular apparatus unit selected, or the proper signal may not be sent 30 from the dispatcher's office and received at the station. In any of these cases, it will be impossible for the control circuit through the polarized relays 217 and 511 to be again completed.

Under these conditions, it is desirable that the selecting apparatus at the dispatcher's office and the selecting apparatus at the station be restored to normal and reoperated in 40 order to cause the selecting apparatus to function properly. In order to accomplish this result, a timing circuit is provided at both the dispatcher's office and station. This timing circuit functions to release and restart the 45 selecting apparatus in a manner that will be explained. The timing circuit is also operative to cause the release and restarting of the selecting apparatus in the event that inductive disturbances cause improper operation in the control circuit itself. That is, the current may flow in the same direction 50 after the control circuit has been interrupted and again completed. This timing circuit is effective to cause the release and restarting 55 of the selecting apparatus in the event that the current in the control circuit does not alternately reverse its direction.

The operation of the timing circuit will 60 now be described, it being assumed that the selecting circuits have failed to function properly for one of the reasons outlined above. When the circuit of the timing relay 213 is completed by the energization of the relay 216, as previously described, the re-

lay 213 is energized and interrupts its own 65 circuit at armature 261, whereupon this relay is deenergized and the armature is released. Inasmuch as the armature 261 is weighted, in 70 its retracting movement, it gains sufficient momentum to carry it into engagement with 75 the other contact, whereby a circuit is completed extending from ground by way of back contact and armature 222, front contact and armature 266, back contact and armature 261, said armature and its back contact, and 80 lower winding of the relay 212 to battery.

The relay 212, with its lower winding energized, attracts the armature 259, whereby 85 a circuit is prepared for the upper winding of said relay. If the relay 216 remains energized, the relay 213 is again energized and attracts armature 261. When the armature 261 disengages its back contact, the short-circuit is removed from the upper winding of the relay 212, and this relay is energized completely 90 to attract the armatures 257, 258 and 260. By the operation of the armature 260, a circuit is prepared for the restarting relay 202, while the operation of the armature 258 prepares a circuit for the slow-releasing relay 210. The operation of the armature 257 prepares a circuit for the upper winding of 95 the relay 204.

Upon the next retraction of the armature 261, if the relay 216 still remains energized, a 100 circuit is completed for the restarting relay 202, for the slow-releasing relay 210, and also for the upper winding of the relay 204. The slow-releasing relay 210 energizes to light the lamp 252, whereby the dispatcher is apprised 105 of the operation of the timing device. The relay 204 operates the armature 235, whereby a circuit is prepared for its lower winding. This winding is not effective until the circuit 110 of its upper winding is opened and the other armatures of the said relay remain in their normal position. The relay 202, upon being energized, operates at armature 290 to prepare a locking circuit for itself, to open the original energizing circuit of the starting relay 207 at armature 289, to complete a circuit for the slow-releasing relay 221 at armature 230, and to open the locking circuit 115 of the relay 207 at armature 228. The operation of the relay 202 also opens the locking circuit of the relay 212 and this relay is deenergized.

The relay 212, upon being deenergized, removes the short circuit from the lower winding 120 of the relay 204, thereby permitting this relay to attract its armatures 233, 234 and 236. By the operation of the armature 233, a circuit is completed for the upper winding of the relay 205. The relay 205 operates to attract its armature 239 which prepares a 125 locking circuit for itself. Another result of the operation of the relay 204 is that, at armature 236, a circuit is completed for the upper

winding of the slow-to-energize relay 203. The relay 207, upon being deenergized, at armature 287 opens the original energizing circuit of the relay 201 and, at armatures 245 and 246, opens the circuit of the relay 209 and prepares a circuit for the relay 206.

At the substation, during this interval, the relay 512 is maintained energized, whereby the timing device 515 is operated. Upon 10 operating, a circuit is completed extending from ground by way of the back contact and armature 587, front contact and armature 549, spring 560, armature 558, armature 562 and its back contact, and lower winding of 15 relay 516 to battery. The relay 516 operates its armature 561, thereby preparing a circuit for its upper winding.

Upon the next energization of the timing device 514, the relay 516 is completely energized, and, upon the deenergization of the timing device, a circuit is completed extending from ground by way of the back contact and armature 587, front contact and armature 549, contact 560, armature 558, contact 25 559, armature 562, and its front contact, and winding of relay 507, to battery. The relay 507 is energized over the above circuit and operates, at its armature 571, to establish a locking circuit for itself, to open the locking circuit of the relay 502 at armature 538, to complete a circuit for the slow-releasing relay 582 at armature 539, at armature 540 to open the locking circuit of the relay 516, and at armature 588 to open the original energizing 30 circuit of relay 502. The relay 502 is immediately deenergized to prepare a circuit for the relay 503.

Another circuit is completed in multiple 40 with that for the relay 503 extending by way of armature 563 and its front contact, back contact and armature 535, and upper winding of relay 505 to battery. The relay 505 operates its armature 534 to prepare a circuit for its lower winding. When the relay 516 is deenergized, the relay 505 is completely 45 operated, whereupon a circuit is closed at 533 for the upper winding of the slow-to-operate relay 506, and at armature 532 a circuit is completed for the upper winding of the relay 504.

A circuit is now completed extending from 50 the negative pole of battery B-4, at the dispatcher's office, by way of armature 237 and its back contact, upper winding of relay 206, back contact and armature 245, winding of line relay 217, conductor 281, winding of the line relay 511, armature 525 and its back contact, upper winding of relay 503, back contact and armature 567, lower winding of relay 503, back contact and armature 526, armature 545 and its back contact, armature 542 and its back contact, armature 541 and its back contact, conductor 280, back contact and armature 275, back contact and armature 60 65 273, back contact and armature 271, armature

246 and its back contact, lower winding of relay 206, and back contact and armature 238 to ground.

The relays 206, 217, 511 and 503 are energized over the above circuit. As a result 70 of the operation of the relay 206, the line relay 217 is shunted in the above circuit, while, by the operation of the relay 503, the line relay 511 is shunted in the above circuit.

Now, when the slow-to-operate relay 203 75 at the dispatcher's office is energized, it opens the locking circuit of the relay 204 at armature 232, thereby permitting this relay to be deenergized. As a result of this operation, the short circuit is removed from the lower 80 winding of relay 205 and this relay is completely operated, whereby the previously traced circuit for the relays 206 and 503 is opened at armatures 237 and 238, at armature 240 a circuit is prepared for the relay 204, 85 and at armature 241 another point in the circuit of the relay 203 is opened. The relay 203 is immediately deenergized to restore certain circuits to normal.

At the substation, the energization of the 90 relay 506 opens the locking circuit of the relay 505, whereupon this relay is deenergized to open the circuit of the relay 506 and to remove the short circuit from the lower winding of the relay 504. The relay 504 is operated to prepare a circuit for the upper winding of the relay 505 at armature 529, to open the previously traced circuit for the relays 206 and 503 at armature 567, and to open another point in the circuit of the relay 506 at 95 armature 531. The slow-releasing relay 582, upon being energized, at armature 587 removes ground from the armature 549, whereby the operation of the timing device is stopped. The operation of the relay 582 also 100 opens the circuit of the relay 512.

Other results of the energization of the relay 503 are that, at armature 589, the locking circuit of the relay 507 is opened and this relay is allowed to deenergize, and at armature 527 a circuit is completed extending from ground by way of armature 588 and its back contact, armature 527 and its front contact, conductor 431, and winding of relay 320 to battery. The relay 320 is energized over the 110 above circuit and operates, at armatures 417 and 418, to remove battery from the battery supply conductor 432 whereby various relays that may have been energized in the counting chain are released.

At the dispatcher's office, the energization of the relay 221 causes the release of the relays 215 and 216, and also the cessation of the operation of the timing device. Another result of the energization of the relay 206 is 125 that, at armature 292, the locking circuit of the relay 202 is opened and this relay is deenergized, while, by the operation of the armature 293, a circuit is completed extending from ground by way of back contact 130

and armature 289, armature 293 and its front contact, conductor 143, and winding of relay 29 to battery. The relay 29 is energized to remove battery from the battery supply conductor 142, whereby the various relays in the counting chain are released.

Now, when the relay 206 retracts its armature, its circuit being open, as previously described, the operation proceeds in the same 10 manner as before described in both the dispatcher's office and the substation.

Continuing now with the description of the operation of the system when it functions properly, the timing devices are not operative. 15 As a result of the operation of the relay 215, previously described, a circuit is completed extending from ground by way of front contact and armature 250, front contact and armature 265, conductor 148, armature 44 and 20 its front contact, back contact and armature 49, lower winding of counting relay 16, back contact and armature 57, back contact and armature 64, back contact and armature 71, back contact and armature 78, back contact 25 and armature 85, back contact and armature 92, back contact and armature 99, back contact and armature 106, back contact and armature 109, and thence to battery by way of armatures 122 and 123.

30 The relay 16 operates over the above described circuit to attract the armatures 47 and 48. By the operation of the armature 48, a circuit is prepared for the upper winding of said relay, while, by the operation of 35 the armature 47, a circuit is completed that extends from ground by way of front contact and said armature, armature 46 and its back contact, conductor 145, and winding of relay 219 to battery. The relay 219, upon being energized, at armature 273 opens one point in the line circuit and, at armature 274, opens the locking circuit of the relay 208, thereby allowing this relay to deenergize. By the 40 opening of the line circuit, the relay 209 is deenergized, whereby the previously traced circuit for the lower winding of relay 16 is opened. The deenergization of relay 208 reverses the connection of the relay 209 with regard to the trunk conductors 280 and 281. The opening of the circuit for the lower winding 45 of the relay 16 causes the complete operation of said relay, inasmuch as the short circuit is removed from its upper winding.

Upon operating, the relay 16, at armature 55 46, opens the previously traced circuit for the relay 219, at armature 49 opens another point in its original energizing circuit, at armature 50 prepares a circuit for the lower winding of the relay 17, and at armature 51 opens the circuit of the relay 15. The relay 50 15 is immediately deenergized to restore certain other circuits to normal.

At the substation, the operation of the armature 546 into engagement with contact 60 547 causes the relay 513 to be energized. The

relay 513, upon being energized, at armature 569 prepares a locking circuit for itself, at armature 553 opens the locking circuit for the relay 512, thereby causing this relay to deenergize, and at armature 552 closes a circuit for the timing device 514. 70

Another result of the operation of the relay 513 is that a circuit is completed extending from ground by way of front contact and armature 520, front contact and armature 554, conductor 426, armature 330 and its front contact, back contact and armature 335, lower winding of relay 301, back contact and armature 344, back contact and armature 351, back contact and armature 358, back contact and armature 365, back contact and armature 372, back contact and armature 379, back contact and armature 386, back contact and armature 393, back contact and armature 396, back contacts and armatures 417 and 418, and 80 thence to battery. 85

The lower winding of the relay 301 is energized over the above-traced circuit to attract the armatures 333 and 334. The operation of the armature 334 serves to prepare 90 a circuit for the upper winding of the relay 301, while the operation of the armature 333 completes a circuit extending from ground by way of front contact and said armature, armature 332 and its back contact, conductor 95 428, and winding of relay 581 to battery. The relay 581 is energized over the above circuit and operates, at armature 585, to establish a locking circuit for itself and to complete a circuit at armature 586 for the relay 100 509.

The relay 509, upon being operated, at armature 542 opens one point in the line circuit, and at armature 543 opens the locking circuit of relay 501. By the opening of the 105 line circuit, the relay 500 is deenergized and the circuit of the lower winding of the relay 301 is opened. This relay is permitted to completely attract its armatures.

By the operation of the armature 332, the 110 previously mentioned circuit for the relay 581 is opened. The operation of the armature 335 opens the original energizing circuit of the relay 301, while the operation of the armature 336 prepares a circuit for the relay 302. The operation of the armature 337 opens the circuit of the relay 300 and the operation of the armature 338 completes a signalling circuit. The relay 300, upon being deenergized, prepares a point in the circuit 115 of the relay 580 at armature 326, prepares another point in the circuit of the relay 580 at armature 327, opens a point in its own locking circuit at armature 328, prepares a circuit for itself at armature 329, opens a point 120 in the circuit of the relay 300 at armature 330, opens a point in the signalling circuit at armature 331, and at armature 480 opens a point in another signalling circuit. 125

By the operation of the armature 338 of 130

the relay 301, a circuit is completed extending from the signalling generator G-2 or G-3, depending upon the position of the apparatus unit associated with this relay armature. 5 Assuming that this armature controls the connection to the generator G-2, an alternating current of a frequency of 900 cycles will be applied over a circuit extending from generator by way of armature 338 and its front 10 contact, winding of the alternating-current relay 314, wave filter F-4, signalling conductor 160, wave filter F, winding of relay 32, armature 125 and its back contact, armature 124 and its back contact, and thence to 15 ground.

The relay 32 is energized over the above-traced circuit and operates, at its armature 126, to complete a circuit extending from the negative pole of battery B through the 20 winding of relay 31, armature 126 and its front contact, front contact and armature 115, winding of the associated polarized relay, and thence to the midpoint of battery B. The polarized relay associated with the armature 115 is operated in the proper manner over 25 this circuit and serves to control the supervisory relays, similar to relays 27 and 28, to cause the operation of the proper supervisory signals, such as 129 and 130. By the 30 operation of the proper relay, the relay 31 is energized and the previously traced circuit for the relays 32 and 314 is opened.

When the relay 314 is energized, a circuit is completed for the relay 508. The relay 35 508, upon energizing, at armature 541, opens another point in the line circuit to prevent the operation of the relays 217 and 511, while the operation of the armature 572 opens the previously traced locking circuit for the relay 581. The relay 581 is deenergized to open 40 the circuit of the relay 509, whereby this relay is allowed to restore to normal, thus completing another point in the line circuit at armature 542 and preparing a locking circuit for the relay 501 at armature 543.

When the alternating-current relay 314 is 45 deenergized, as above described, the circuit of the relay 508 is opened, and this relay restores to complete the circuit of the line relays over a path which is the same as that originally traced.

The apparatus continues to function in the 50 manner described. The counting relays in the relay group RG at the dispatcher's office, such as relays 17 to 24, inclusive, are energized in the same manner, while the relays 302 to 309, inclusive, in the relay group RG-1 at the substation are operated in the same sequence in substantial synchronism with the 55 relays in the relay group RG. These actions take place under the control of the controlling relays, as described.

At the dispatcher's office, the relay 215 will 60 be operated to cause the energization of the last counting relay 24, while, at the substa-

tion, the relay 513 is operated to cause the energization of the relay 309.

The relay 24, upon being energized, prepares a circuit for the relay 25 at armature 105, at armature 106 opens the circuit of the 70 relay 23, at armature 107 prepares a circuit for the polarized relay associated with it, and also prepares a signalling circuit, and at armature 101 the circuit of the relay 219 is opened and the line circuit is restored to 75 normal.

At the substation, the operation of the relay 309, at armature 388, opens the circuit of the relay 581, at armature 392 prepares a circuit for the relay 310, at armature 393 80 opens a circuit for the relay 308, and at armature 394 completes a signalling circuit, including the relay 314 and the relay 32 or 33 at the dispatcher's office, as the case may be, depending upon the condition of the apparatus unit associated with the armature 394.

Upon the operation of the required supervisory signal, the relay 30 or 31, as the case may be, is operated to open the signalling circuit and to permit the deenergization of 90 the relay 314, whereby the relay 508 is allowed to restore to normal. The circuit for the relays 209, 217, 511 and 500 is now completed. The armature of the relay 217 is operated into engagement with the contact 276, while 95 the armature of the relay 511 is operated into engagement with the contact 548.

By the energization of the relay 216, a circuit is completed extending from ground by way of the front contact and armature 250, 100 front contact and armature 269, conductor 147, armature 105 and its front contact, winding of relay 25, and thence, by way of armatures 122 and 123 and their back contacts, to battery. The relay 25, upon being energized, 105 at armature 108 completes a circuit extending from ground by way of front contact and said armature, conductor 141, and winding of relay 202 to battery.

The relay 202 is energized over the above 110 circuit and operates to establish a locking circuit for itself at armature 290. The relay 202 now functions to open the original energizing circuit and also the locking circuit of the relay 207, whereby this relay is restored 115 to normal. The slow-releasing relay 221 is also energized to cause the release of the relay 216. The deenergization of the relay 207 opens the original energizing circuit of the relay 201 at armature 287 and prepares a circuit for the relay 206.

At the substation, the operation of the relay 512 completes a circuit extending from ground by way of the front contact and armature 520, front contact and armature 551, 125 conductor 425, armature 392 and its front contact, winding of relay 310, and thence, by way of the back contacts and armatures 417 and 418, to battery. Upon operating, the relay 310 opens the circuit of the relay 309 130

and at armature 399 a circuit is completed extending from ground by way of front contact and said armature, conductor 433, and winding of relay 507 to battery. The relay 507 is energized over the above-traced circuit and operates, at armature 571, to establish a locking circuit for itself and, at armature 539, to complete a circuit for the slow-releasing relay 582. The relay 582 is operated to 10 open the circuit of the relay 512, which is deenergized.

The relay 507 also opens the original energizing circuit of the relay 502, and, also, its locking circuit.

15 The relay 502 is thus deenergized and a circuit is completed extending from battery B-4, at the dispatcher's office, by way of armature 237 and its back contact, upper winding of relay 206, back contact and armature 245, winding of relay 217, conductor 281, winding of relay 511, armature 525 and its back contact, upper winding of relay 503, back contact and armature 567, lower winding of relay 503, back contact and armature 526, armature 545 and its back contact, armature 542 and its back contact, armature 541 and its back contact, conductor 280, back contact and armature 275, back contact and armature 273, back contact and armature 271, armature 246 and its back contact, lower winding of relay 206, back contact and armature 238, and thence to ground.

35 The relays 206 and 503 are energized over the above-traced circuit. The relay 206 operates to open the locking circuit of the relay 202 at armature 292, whereby this relay is deenergized, and at armature 293 completes a circuit for the relay 29, whereby battery is removed from the battery supply conductor 142. Another result of the operation of the 40 relay 206 is that the polarized line relay 217 is short circuited.

At the substation, the energization of the relay 503 causes the locking circuit of the relay 507 to be opened and this relay is deenergized to cause a circuit to be completed for the relay 320, whereby battery is removed from the battery supply conductor 432 and the line relay 511 is short circuited.

50 In the above manner, the apparatus is restored to normal, responsive to the sending of supervisory signals to check all the positions of the various apparatus units that are being supervised in the station or substation. It will be clear that the action of the control circuit is interrupted upon each operation of any counting relay at the dispatcher's office and station, inasmuch as the signalling circuit is completed upon the operation of any one relay in the counting relay groups. The purpose of completing this signalling circuit is to check, at all times, the condition of the dispatcher's signalling devices so that they correspond to the condition 60 of the apparatus units at the station. In the

event that the apparatus does not function properly, the line relays 217 and 511 are held in position and the timing devices function to release and restart the apparatus in the manner described.

70

In the foregoing description of the operation of the system, it has been assumed that the apparatus unit changed condition at the substation.

To describe the operation when the dispatcher desires to operate an apparatus unit, it will be assumed that the dispatcher operates the key K, which is associated with the desired apparatus unit, in such direction as to apply the voltage of the generator G-1 75 80 to the armature 45 of the counting relay 15. The dispatcher will now operate the start key K-1 momentarily. By this operation, an impulse of current is sent over a circuit extending from ground through the spring of this key, conductor 140, armature 240 and its back contact, and upper winding of relay 205 to battery. The relay 205 is operated over the above circuit to attract the armature 239, whereby a circuit is prepared 85 90 for the lower winding of said relay. When this ground impulse terminates, the relay 205 is completely operated. Another result of this operation is that a circuit is prepared for the restart relay 204 extending the circuit from K-1, line 140, armature 240, armature 234, upper winding of 95 204, battery, ground, and the line circuit is broken. The key K-1, it is understood, is closed twice. The relays 206 and 503 are thus deenergized. 100 The apparatus functions in the same manner as before described.

When the relay 15 in the counting chain at the dispatcher's office is completely operated, the relay 300 at the substation will also be 105 operated. Now, as a result of the key K being thrown, there will be a circuit completed extending from the generator G-1 by way of the key spring contacts, armature 45 and its front contact, winding of relay 34, wave filter F-2, signal conductor 160, wave filter F-3, winding of the alternating-current relay 316, armature 411 and its back contact, armature 412 and its back contact, and thence to ground.

115

The relays 316 and 34 are energized over the above-traced circuit. As a result of the operation of the relay 34, a circuit is completed extending from ground by way of armature 128 and its front contact, conductor 144, and, through the winding of the relay 220, to battery. The relay 220 is energized over the above circuit and operates to open one point in the circuit of the line relays at armature 275.

125

At the substation, the operation of the relay 316 completes a circuit extending from the positive pole of the battery B-5 through the winding of relay 317, armature 410 and its front contact, front contact and arma-

130

ture 331, winding of polarized relay 319, and to the midpoint of the battery B-5.

It will be assumed that the armature 413 of the polarized relay 319 is operated into engagement with the contact 414. As a result of this operation, the relay 311 is energized. The relay 311, upon being operated, at armature 390, establishes a locking circuit for itself, and at armature 391 completes a circuit for the closing coil 323 of the circuit breaker C. The relay 317 is also energized over the above circuit for relay 319 and operates to remove ground from the signalling circuit whereby the relay 316 is deenergized, as is the relay 34 at the dispatcher's office. By the deenergization of the relay 34, the circuit of the relay 220 is opened and this relay is permitted to deenergize to complete one point in the line circuit. If the supervisory apparatus has functioned properly, the line circuit will be closed and the polarized line relays operated in the same manner as that before described.

When the circuit breaker C closes, the relay 313 is energized, and the locking circuit of the relay 311 is opened and this relay is deenergized. When a circuit is completed for the closing coil 323 of the circuit breaker C, the relay 321 is momentarily energized and the starting relay 504 is operated. The operation of this relay is without particular function at the present time, inasmuch as the circuit has already started to function.

Of course, at the same time that the dispatcher is causing the operation of the apparatus unit, the apparatus unit being in an open condition, the signalling current from the generator G-2 will be applied to the signalling circuit in order to inform the dispatcher of the condition of the apparatus unit before it is operated. That is, at the same time the circuit is completed for bringing about the operation of the apparatus unit, a circuit is completed, extending to the dispatcher's office, that checks the indication given by the signalling devices at the office. The condition of the signalling devices is thus momentarily checked before the condition of the circuit interrupter is changed. In the event that the signalling devices would, for some reason or other, indicate that the circuit interrupter was closed when, in reality, it was open, and the dispatcher desires to close the circuit interrupter, the operation will take place in the same manner as described. However, when the desired apparatus unit is selected by the operation of the counting relays, a signalling circuit will be completed which will change the supervisory signalling devices to indicate the true condition of the unit. The circuit that the dispatcher completes to bring about the operation of the unit will not be effective by reason of the fact that the apparatus unit or circuit interrupter will already be in that position. Un-

der these conditions, only the indication given by the signalling devices will be changed.

The foregoing is the normal operation of the system. However, it is possible, under certain conditions, that the signalling circuit will not function properly. This may be caused by open circuit or other conditions. In this event, considering that the dispatcher is sending a supervisory signal, the alternating-current relay 153 in series with the artificial line L-1 will be energized to complete a circuit extending from ground by way of front contact and armature 162, armature 155 and its back contact, armature 165 and its back contact, and upper winding of the slow-to-energize relay 152 to battery.

If the relay 34 does not operate before the relay 152, which is slow to operate, the relay 151 is energized to complete a circuit for the buzzer alarm 150 and to establish a locking circuit for itself. The relay 153 is placed in circuit with an artificial line L-1 which has the same impedance and other constants as the signalling conductor 160 has normally. The time of energizing of the relays 34 and 153, under normal conditions, will be substantially the same, and the alarm will not sound unless there is trouble in the signalling circuit. By the operation of the signalling device 153, the dispatcher is informed that there is a fault on the signalling conductor 160 and he may have this corrected. When the trouble is cleared, the dispatcher may stop the alarm by operating the key K-3.

In a like manner, the relay 440 at the substation will cause the operation of the buzzer alarm 443 and the lighting of the lamp 452 in the event that the relay 314 does not energize within a sufficient time, as determined by the period of time that it requires the slow-to-operate relay 441 to attract its armature. This provides that, in the event that the supervisory signals do not traverse the circuits properly, the attention of the operator at the station may be directed to such failure. If the dispatcher operates a key while the relay selecting apparatus is operating, and after it has selected the key that is operated, it will be seen that there will be no operation of the desired apparatus unit during this cycle of the selecting apparatus. After the selecting apparatus has restored to normal, the dispatcher will again operate the start key, thereby bringing about the operation of the relay chains and the desired apparatus unit. Should a circuit interrupter or apparatus unit at the station be operated while the relay chains are operating, after having been started from the dispatcher's office, the relay 321 at the station will be momentarily energized. If the relay chains have already selected this apparatus unit, no indication of the operation of the circuit interrupter will be sent to the dispatcher's office until the re-

lay chains go through another selecting operation, either by reason of the operation of a second apparatus unit, or under the control of the dispatcher. If a second apparatus unit is not operated during this cycle of the selecting apparatus, the signalling devices at the dispatcher's office will, of course, indicate a condition of the apparatus unit opposite from its true position. However, this will bring about no false operation for the reason that, should the dispatcher, seeing that the apparatus unit is in its closed position, according to the signalling devices, try to open it, there will be no operation. This follows from the previous explanation in view of the fact that the circuit that is closed to open the apparatus unit will be ineffective.

In the system just described, the number of circuit breakers that may be controlled and supervised is limited to ten. There are a number of methods of increasing the capacity, one simple method being by enlarging the counting relay chain at both the dispatcher's office and the substation by adding one relay for each apparatus unit that it is desired to operate. When this is done, only the three conductors shown are used, the two control conductors and the signalling conductor connecting the dispatcher's office and the substation. Another method is by increasing the number of frequencies of alternating current and filters in the signalling circuit in an obvious manner. A third method of accomplishing the same result involves the addition of another signalling conductor for each ten apparatus units added. In addition, for each signalling conductor added, there is a pair of contacts on each of the relays in the counting chain. Of course, in all the cases mentioned, additional polarized relays and controlling relays are required.

The third method is illustrated diagrammatically in the drawings, the conductor 159 being the additional signalling conductor added. This conductor is provided with wave filters F-6, F-7 and F-8 at the dispatcher's office and wave filters F-9, F-10 and F-11 at the substation. In addition, the counting relays are provided with extra contacts 171 to 174 on the relays 15 to 18, inclusive, at the dispatcher's office and the contacts 480 to 484, inclusive, on the relays 300 to 304, respectively, at the substation. In this case, the operation is substantially the same as that before described, with the exception that, for each operation of a counting relay, two operations in both directions may occur instead of one.

Attention is drawn to the fact that, inasmuch as alternating current of a predetermined frequency is employed for signalling purposes, any induced disturbance in the signalling conductor, unless it is of one of the predetermined frequencies and exists long

enough to cause the operation, will have no effect on the signal. The possibility that an induced disturbance will be of one of the predetermined frequencies and will exist for an interval sufficiently long to cause an operation, is exceedingly remote.

It will be seen, also, that, inasmuch as the operating circuits are controlled by positive and negative impulses following each other, any induced disturbances on these conductors will not cause a false functioning of the counting relay chain at either end for the reason that, unless a positive impulse follows a negative impulse within a predetermined time, the apparatus is released and the operation restarted.

Our invention is not limited to the particular arrangement of the apparatus illustrated but may be variously modified without departing from the spirit and scope of our invention, as set forth in the appended claims.

We claim as our invention:

1. In an electrical control system, the combination with a control office, a station, a group of relays at the control office and a corresponding group of relays at the station, means including a circuit between the office and station, and current-direction-responsive means associated with the circuit for operating predetermined relays in each of said groups simultaneously, a source of current, means for so connecting said source of current to said circuit that the current flows alternately first in one direction and then in the other, and means operative in the event that the reversal of current in said circuit does not occur within a predetermined time interval for restoring the relays in each of said groups to their normal condition.

2. In an electrical control system, the combination with a control office, a station, a group of relays at the control office and a corresponding group of relays at the station, means including a circuit between the office and station, and current-direction-responsive means associated with the circuit for operating predetermined relays in each of said groups simultaneously, a source of current, means for so connecting said source of current to said circuit that the current flows alternately first in one direction and then in the opposite direction, means operative in the event that the reversal of current in said circuit does not occur within a predetermined time interval for restoring the relays in each of said groups to their normal condition, and means for thereafter causing the operation of the relays in either group.

3. In an electrical control system, the combination with a control office, a station, and a group of relays at the control office and a corresponding group of relays at the station, of means including a polarized relay at the control office and a corresponding relay at the station for controlling the operation

- of the relays in their respective groups, a circuit including said relays for controlling both of said last-named relays, a source of electric current, means for causing current from said 5 source to alternately flow through said circuit in opposite directions to operate the last-named relays, means controlled by the last-named relays for operating predetermined relays in each of said groups simultaneously, 10 means operative in the event that the reversal of current in said circuit does not occur within a predetermined time interval for restoring the relays in each of said groups to their normal condition, and means for thereafter causing the operation of relays in either group. 15
4. In an electrical control system, the combination with a control office and a substation, of a chain of relays at the office and at the station, a line relay at said office, a line 20 relay at said substation, a circuit including said line relays for controlling said line relays, means for applying impulses of current to said circuit, another relay associated with each of said line relays for controlling the operation of the relays in the associated 25 chain of relays, means controlled by said line relays for operating said other relays, and locking circuits for said other relays effective until the next subsequent operation 30 of the respective associated line relay.

5. In an electrical control system, the combination with a control office and a station, of a chain of relays at said office, a chain of relays at said station, a polarized line relay at 35 said office and at said station, a first and a second relay associated with each of said line relays, means for operating said first relay in one position of the associated line relay, means for operating said second relay 40 in the other position of said line relay, means controlled jointly by said first and second relays for operating all the relays in the associated chain of relays, a locking circuit for said first relay effective until the operation 45 of said second relay associated with said line relay, a locking circuit for said second relay effective until the operation of said first relay, a circuit for said line relays, and means for supplying electric current over said circuit in opposite directions alternately to operate 50 said line relay.

6. In an electrical control system, the combination with a control office, a station and a plurality of apparatus units in said station, of a chain of relays at the said office and at the said station, impulsing means for operating the relays in the chain at said office in a definite sequence and for operating the relays in the chain at the substation in synchronism 55 and simultaneously therewith, means controlled by any relay in the chain at said station for selecting one of said apparatus units, means for stopping the operation of said impulsing means until such selection has occurred, and means operatively responsive to

such selection for again causing said impulsing means to function.

7. In an electrical control system, the combination with a control office, a station and a plurality of apparatus units in said station, of a chain of relays at the said office and at the said station, impulsing means for operating the relays in the chain at said office in a definite sequence and for operating the relays in the chain at the station in synchronism and simultaneously therewith, means controlled by any relay in the chain at said station for selecting one of said apparatus units, and means for intermittently interrupting the operation of said impulsing means after the 75 operation until each selection is made.

8. In an electrical control system, the combination with a control office and a station, of a plurality of signalling devices in said office, a plurality of apparatus units at said station, a relay group at the said office and at the station, means for operating the relays in the chain at said office in a definite sequence, means for operating the relays in the chain at the station in synchronism therewith, means controlled by the operation of any one of said relays in the chain at said station for selecting one of said apparatus units, means controlled by the operation of the corresponding relay in the chain at said 90 office for selecting one of said signalling devices, mechanism controlled by the condition of said selected unit for operating said selected signalling device, and means operative following the operation of said signalling device for stopping the operation of said impulsing means until said signalling device has operated.

9. In an electrical control system, the combination with a control office and station, of a plurality of apparatus units at said station, a chain of relays at the said office and at the said station, means at said office for operating the relays in the chain therat in a definite sequence, means for operating the relays in the chain at the station in the same sequence, a plurality of signalling devices at said office, one for each of said units, means controlled by the operation of any relay in the chain at said station for selecting one of said units, means controlled by the operation of the corresponding chain in the relay at the office for selecting one of said signalling devices corresponding to the apparatus unit selected, means for thereafter operating said signalling device in accordance with the condition of one of said unit, and means for stopping the operation of said impulsing means until said signalling device has been completely operated.

10. In an electrical control system, the combination with a control office, a station and a plurality of apparatus units at said station, of a plurality of keys at the said office, one corresponding to each of said units, a 120 125 130

chain of relays at the said office and at the said station, respectively, means for operating the relays in the chain at said office in a definite sequence, means for operating the 5 relays in the chain at said station in synchronism therewith, means controlled by the operation of a relay in the chain at said station for selecting one of said apparatus units, means controlled by the corresponding relay 10 in the chain at said office for selecting one of said keys corresponding to the unit selected, means for operating said apparatus unit in accordance with the position of its corresponding key, and means for stopping the 15 operation of said relay chains until such operation has occurred.

11. The combination with a control office, a station and a plurality of apparatus units in said station, of a plurality of signalling 20 devices at said office, one for each of said units, a relay chain at the said office and at the said station, means for operating the relays in the chain at said office in a definite sequence, means for operating the relays in the 25 chain at said station in the same sequence simultaneously, means controlled by the operation of a relay in said relay chain at said station for selecting one of said units, means controlled by the corresponding relay in the 30 chain at said office for selecting a corresponding signalling device, a signalling circuit connecting said office and station, means controlled over said signalling circuit for operating said signalling device in accordance 35 with the condition of said unit, means for simultaneously operating the selected unit over said signalling circuit, and means for stopping the operation of the relays in said chain until both the unit and signalling device 40 have operated.

12. In an electrical control system, the combination with a control office, a substation and a plurality of apparatus units in said substation, of a plurality of signalling devices at said office, one for each of said units, of a chain of relays at the said office and at the said substation, means for operating the corresponding relays in both chains simultaneously in a definite sequence, means controlled by the operation of a relay in the 45 chain at said station for selecting a predetermined apparatus unit, means controlled by the operation of the corresponding relay in the chain at said office for selecting the signalling device associated with said unit, an alarm signalling device, means for operating the selected unit from said circuit, and means operated in the event that said unit is not operated within a predetermined time 50 for operating said alarm signalling device.

13. In a signalling system, a first station, a second station, a chain of relays at each station, a circuit connecting said stations, means including said circuit for operating 55 one of said relays at the first station and its

associated relay at the second station, means operative responsive to the operation of said relays for terminating the operation of said first-mentioned means, means operative following the termination of the operation of 70 said first-mentioned means for preparing the succeeding relay at each of said stations for operation and for again operating said first-mentioned means for operating the succeeding relay at each station. 75

14. In a signalling system, a first station, a second station, a chain of relays at said first station, a chain of relays at said second station individual to said relays at said first station, a closed driving circuit connecting said 80 stations, means including said closed driving circuit for operating a relay at said first station and its associated relay at said second station, means operative in response to the operation of said relays for opening said 85 driving circuit, means responsive to the opening of said driving circuit for preparing the succeeding relay in each chain for operation by a closed driving circuit and for again closing said driving circuit, said first-mentioned means being therefore operative to 90 energize the succeeding relay in each chain.

15. In a supervisory control system, a first station, a second station, apparatus units at said second station, signalling devices individual thereto at said first station, synchronously operated selector devices at said first and said second station for associating each of said apparatus units with its associated signalling device whereby said signalling device is operated in response to the operation 95 of said apparatus unit and means whereby said selecting apparatus is momentarily stopped until said signalling device completely operates in response to the operation 100 of said apparatus unit. 105

16. In a supervisory control system, a first station, a second station, a signalling line connecting said stations, a plurality of apparatus units at said second station, each having a plurality of positions, a plurality of signalling devices, individual thereto at said first station, for indicating the position of said units, a signalling line connecting said stations, synchronous selector devices for simultaneously associating an apparatus unit and its associated signalling device with said signalling line and means for maintaining said connection until said signalling device indicates the condition of said unit. 115 120

17. In a supervisory control system, a first station, a second station, apparatus units at said second station operable to a plurality of positions, signalling devices, individual thereto at said first station, responsive to the operation of said units, a signalling line connecting said stations, normally non-operating synchronous selectors at said first and said second station, means responsive to the operation of one of said apparatus units for start- 125 130

- ing said synchronous selectors into operation, means including said synchronous selectors for associating said operated apparatus unit to its associated signalling device, and means for maintaining said connection until said signalling device has operated in response to the operation of said apparatus unit.
18. In a supervisory control system, a first station, a second station, apparatus units at said second station, each of said units having a plurality of conditions, signalling devices at said first station individual thereto for indicating the condition of said units, synchronous selecting device for consecutively associating each apparatus unit with its signalling device and means for maintaining each of said connections until the signalling device indicates the condition of its individual apparatus unit.
19. In a supervisory control system, a first station, a second station, apparatus units at said second station, each of said units being operable to a plurality of positions, signalling devices at said first station for indicating the positions of said units, synchronously operating selector devices for consecutively associating each of said apparatus units with its individual signalling device and means operative responsive to a change of any one of said apparatus units for maintaining the connection of said unit to its associated signalling device until said device is correctly operated.
20. In a supervisory control system, a first station, a second station, apparatus units at said second station, signalling devices individual thereto at said first station, synchronously operated selector devices for consecutively associating each of said apparatus units with its individual signalling device, said selectors being normally in a non-operating condition, and means responsive to the operation of any one of said apparatus units for starting said selectors into operation, a drive line connecting said stations, means controlled by said selector devices operating in synchronism for transmitting impulses over said drive line and means responsive to said impulses for operating said selector devices in synchronism.
21. In a supervisory control system, a first station, a second station, apparatus units at said second station, each of said units having a plurality of positions, signalling devices individual thereto at said first station for indicating the positions of said units, normally non-operating synchronous selectors, means whereby said selectors may be started into operation from said first station, means including said selectors for selectively operating said apparatus units from said first station, means whereby, when said selectors are started into operation, they make a complete cycle and are restored to non-operating conditions, means whereby said selectors may be started by an automatic operation of one of said units from said second station, and means whereby said selectors, during said single cycle of operation, will cause each of the signalling devices to indicate the then position of their individual apparatus units.
22. In a supervisory control system, a first station, a second station, apparatus units at said second station, signalling devices individual thereto at said first station, normally non-operating synchronous selectors, means whereby said selectors may be started into operation from said first station, means whereby said selectors may be started by an automatic operation of one of said units from said second station, means including said selectors for operating one of said apparatus units from said first station and means including said selectors responsive to the operation of said apparatus unit for operating one of said signalling devices.
23. In a supervisory control system, a first station, a second station, apparatus units at said second station, signalling devices individual thereto at said first station, a signalling line connecting said stations, means for selectively operating said apparatus units from said first station, means including said signalling line for operating said signalling devices in response to the operation of said apparatus units and means operative should said signalling line fail to transmit said signals, for providing an indication thereof.
24. In a supervisory control system, a first station, a second station, apparatus units at said second station, signalling devices individual thereto at said first station, a signalling line connecting said stations, means including said signalling line for transmitting an impulse to operate one of said apparatus units, and means operative should said impulses fail to be transmitted for providing an indication thereof.
25. In a supervisory control system, a first station, a second station, apparatus units at said second station, signalling devices individual thereto at said first station, a signalling line connecting said stations, means for transmitting impulses over said signalling line for controlling and supervising said apparatus units and means operative should said signals fail to be transmitted for providing an indication thereof.
26. In a signalling system, a first station, a second station, a chain of relays at said first station, a chain of relays at said second station, a driving circuit connecting said stations, means for transmitting impulses over said driving circuit, means operative in response to said impulses for operating said relays at each station simultaneously and in synchronism, and means whereby said impulses are transmitted only when said chains of relays are in synchronism.

27. In a signalling system, a first station, a second station, a chain of relays at said first station, a chain of relays at said second station, a driving circuit connecting said stations, means including circuit arrangements at said stations whereby impulses transmitted over said driving circuit synchronously and sequentially energize the chains of relays at each station, and means including circuits at each station controlled by said relays at each station whereby impulses are transmitted over said driving circuit.

28. In a signalling system, a first station, a second station, a chain of relays at said first station, a chain of relays at said second station, a driving circuit connecting said stations, impulse transmitting means for transmitting impulses over said driving line, means responsive to said impulses for synchronously energizing said relays at each station, and means whereby said impulse transmitting means is operated to transmit impulses only when said chains of relays are in synchronism.

29. In a signalling system, a first station, a second station, a chain of relays at said first and said second station, means including a driving circuit for operating said relays in synchronism, means whereby said chains of relays control said driving circuit, and means should said chain of relays fall out of synchronism for rendering said driving circuit ineffective for driving.

30. In a signalling system, a first station, a second station, a chain of relays at said first and said second station, a driving circuit connecting said stations, means including said chains of relays for intermittently transmitting impulses over said driving circuit, means responsive to said intermittent impulses for operating said chains of relays in synchronism, means operative should said chain of relays fall out of synchronism, for stopping said intermittent impulses, and means operative should said impulses stop in response to a non-synchronous condition for restoring said relays to normal.

31. In a signalling system, a first station, a second station, a chain of relays at said first and said second station, a driving circuit connecting said stations, means including said chains of relays for intermittently transmitting impulses over said driving circuit, means responsive to said intermittent impulses for operating said chains of relays in synchronism, means for stopping said intermittent impulses, and means operative should said impulses stop in response to a non-synchronous condition for restoring said relays to normal.

32. In a supervisory control system, a first station, a second station, automatically operable apparatus units at said second station, signalling devices individual thereto at said first station, normally non-operating select-

ing apparatus at said first and said second station for selecting one of said apparatus units, means responsive to an automatic operation of one of said apparatus units for starting said selecting apparatus at each station into operation, means including said selectors for selectively operating the signalling devices individual to said apparatus unit in response to its operation and means including said selectors for selectively operating said apparatus unit from said first station.

33. In a supervisory control system, a first station, a second station, automatically operable apparatus units at said second station, signalling devices individual thereto at said first station, normally non-operating selectors at said first and said second station, means for starting said selectors into operation from either of said stations, in response either to an automatic operation of one of said units or a manual operation from said first station, means including said selectors for selectively operating one of said apparatus units from said first station, and means including said selectors in operation for selectively operating any one of said signalling devices in response to the operation of said apparatus unit.

34. In a supervisory control system, a first station, a second station, automatic apparatus units at said second station, signalling devices individual thereto at said first station, normally non-operating chains of relays at said first and said second station, means for starting said chains of relays into operation from either of said stations in response either to an automatic operation of one of said units or a manual operation from said first station, means including said chains of relays for selectively operating one of said apparatus units from said first station and means including said chains of relays in operation for selectively operating any one of said signalling devices in response to the operation of said apparatus unit.

35. In an electrical control system, the combination with a control office, a station and a plurality of apparatus units in said station, of a chain of relays at said office and station, respectively, impulsing means for operating the relays in the chain at said office in a definite sequence, and for operating the relays in the chain at the station in synchronism and simultaneously therewith, means controlled by any relay in the chain at said station for selecting one of said apparatus units, and means for stopping the operation of said impulsing means until such selection has occurred.

36. In a supervisory control system, a first station, a second station, apparatus units at said second station, signalling devices individual to said apparatus units at said first station, normally non-operating synchronous

selectors at said first and said second station for selecting one of said apparatus units for operation from said first station, each of said selectors having a normal position, means at 5 said first station for starting said selecting apparatus into operation, means controlled by said selectors for operating each of said selectors to the first and each successive equivalent selecting positions simultaneously, means including said selectors for selectively operating said apparatus units from said first station and means including said selectors for 10 operating said signalling devices in response to the operation of said apparatus units and means whereby said selectors restore to non-operating condition at their normal position at the completion of a cycle.

37. In a signalling system, a first station,

a second station, a relay chain at each station, impulsing means associating said stations for operating equivalent relays of said chains simultaneously, and circuit arrangements whereby operation of equivalent relays operates to transmit said impulses.

38. In a signalling system, a first station, 25 a second station, a chain of relays at each of said stations, electrically interconnected means for energizing equivalent ones of said chains of relays simultaneously, said means being controlled by said chain of relays. 30

In testimony whereof, we have hereunto subscribed our names this 28th day of January, 1924.
